UNITED STATES PATENT OFFICE

HORACE B. FAY, OF CLEVELAND HEIGHTS, OHIO, ASSIGNOR TO THE BISHOP & BABCOCK MANUFACTURING COMPANY, OF CLEVELAND, OHIO, A CORPORATION OF OHIO

CONTROL MEANS FOR COOLING SYSTEMS FOR INTERNAL-COMBUSTION ENGINES

Application filed March 20, 1926. Serial No. 96,207.

The present invention, relating, as indicated, to control means for cooling systems for internal combustion engines is particularly directed to means associated with the cooling 5 or circulating system of an internal combustion engine, such, for example, as a hydro-carbon engine employed in a vehicle, for the purpose of proportioning the flow of cooling fluid to the temperature existing in the 10 system, and particularly in the jacket for the one or more cylinders which constitute the engine. A further object of the invention is the provision of such means for controlling the circulation in such a way as to cause that 15 portion of the circulating fluid, which is initially in the cooling jacket and the portions of the circuit closely adjacent thereto, to be brought to the desired temperature as quickly as possible and without affecting the 20 operation of the entire cooling circuit or of any portions of the engine, such for example as the circulating means or pump.

To the accomplishment of the foregoing and related ends, said invention, then, consists of the means hereinafter fully described and particularly pointed out in the claims; the annexed drawing and the following description setting forth in detail certain mechanism embodying the invention, such 25 30 closed means constituting, however, but one of various mechanical forms in which the principle of the invention may be used.

In said annexed drawing:—

Fig. 1 is a side elevation of an internal combustion engine provided with a cooling system and having associated therewith my control means; Fig. 2 is a transverse central section through one form of valve mechanism of my control means; and Fig. 3 is a similar 40 view showing a modified type of valve.

Referring now to Fig. 1 there is shown a multi-cylinder internal combustion engine 1, in which a number of cylinders are formed integral with each other and are each 45 rounded with the usual cooling jacket for receiving a cooling fluid, these jackets discharging into a common conduit or manifold 2 connected by means of a conduit 3 to a radiator from which the fluid returns through 50 conduit 5 to a pump 6 and then through con-

duit 7 into the lower portion of the cylinder jackets. The pump 6 may be of any suitable construction and may be operated by any suitable type of drive, which is too common to require illustration.

Extending from the upper conduit 3 to the lower conduit 5 is a by-pass conduit 8 which, when placed in communication with the conduits 3 and 5, provides an interior circuit which eliminates the radiator and permits of a shortened circulation of the cooling fluid, in which the fluid first flows upwardly through the cylinder jackets, then through the manifold 2, part of the conduit 3, the by-pass 8 and through the pump 6 and conduit 7 back into the lower portion of the jackets. In this shortened or interior circuit there is of course no cooling means for the fluid, such for example as the radiator 4, so that the fluid, while traveling through this interior circuit is not cooled appreciably and retains most of the heat which it acquires as it rises through the cooling jackets of the cylinders.

My improved control means consist of this by-pass conduit 8, which disconnects the radiator from the circulating circuit and the controlling valves 16 and 11 now to be described. Valve 16, which is thermostatically controlled, is interposed in a suitable casing 12 disposed in the upper conduit 3, through which the water flows on its way from the manifold 2 to the top of the radiator 4. This valve mechanism consists of an open cylindrical framework or cage 13, within which is mounted a sealed hollow expandible and contractible member or bellows 14 having one end fixed to the outer end of the casing 13, while its other end is secured to a stem 15, on which is mounted a valve 16. The bellows member 14 is normally filled under a vacuum and is therefore contracted and constructed to hold the valve 16 against a seat 17 which completely closes the casing 12 against the flow of the circulating liquid therethrough. Upon a predetermined increase in the temperature of the bellows 14, produced from the temperature of the surrounding water which contacts the bellows through the openings in the sides of the case 13, the expandible liquid contained within the bellows expands

and lifts the valve 16 from off its seat, establishing communication between the conduit 3 and the radiator 4, and thus permitting the flow of the circulating fluid through the entire cooling circuit, including the radiator.

Disposed in the by-pass 8, and preferably adjacent to the thermostatically controlled valve, is a pressure-controlled valve 11, which is normally held against its seat 18 by means of a spring 19. This valve normally closes communication through the by-pass 8 and under certain conditions, including the time when the engine is not operating and also when the circulating fluid is below the desired operating temperature after operation has begun, both of the valves are closed and the circuit is then a closed circuit, through which there can be no circulation. As soon as the engine is operated the pump 6 acts to force the water through the cooling jackets, through the conduits 2 and 3 and against the valves 16 and 11. The thermostatically controlled valve is seated with sufficient pressure so that it does not open under any pressure obtainable by the pump, but the pressure controlled valve 11 is constructed to permit this valve to unseat and permit circulation through the interior circuit as soon as a predetermined pressure is reached, and this pressure may be anything that is decided upon, since the strength of the closing spring 19 can of course be varied to suit practically any conditions.

Assuming now that the engine has been inoperative for a sufficient time to permit all of the cooling water to reach a low temperature, after which the engine is started, the pump will at once be operated to pass fluid through the circulating system, and since both of the valves are initially closed, a pressure will rapidly be built up until, at a predetermined point, this pressure will force open the valve 11 and allow communication between the conduits 3 and 8. Under this condition the circulating liquid will be circulated through the interior circuit and will not be appreciably cooled so that all of the water in the interior circuit will be rapidly heated to the desired temperature, after which the thermostatic valve 16 will be opened by the bellows, allowing the entire circuit to function and also relieving the pressure on the pressure valve 11, which will then close and remain closed until the same conditions again occur, as, for example, when the engine has been stopped for sufficient time to cool the circulating liquid below the opening temperature of the thermostatic valve 16.

The advantages of the present system will be apparent since it permits of a perfectly free circulation under normal operating conditions when the circulating liquid has been brought to the desired temperature, while at the same time entirely preventing any material loss of heat from the circulating

liquid during the initial warming-up period of the engine, at which time it is very desirable that fresh cold circulating liquid be excluded from the jackets of the engine. Otherwise the engine will require a very much longer period to warm up, and during all of this period there will be condensation of the fuel in the combustion chamber and resultant leakage of this fuel past the pistons, causing a dilution of the crankcase lubricant as well as ineffective operation of the engine.

In Fig. 3 I have shown a modification of my improved cooling system in which the by-pass conduit 8 is normally open instead of closed, but is gradually closed upon the expansion of the thermostat 14, and the opening of the thermostatically controlled valve 16 by means of a slide or valve 25, which is provided with a port 26 normally in registration with the conduit 8. As the thermostat expands and opens the valve 16 the slide 25 is moved to the left and the port 26 is gradually brought out of registration with the conduit 8, after which this conduit is closed and remains closed until the liquid has cooled to a point permitting the contraction of the bellows to again bring into registration the port 26 and the conduit 8. In both Figs. 2 and 3 the direction of flow of the cooling liquid is indicated by the attached arrows.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In combination with an internal combustion engine, a cooling system therefor, comprising a fluid cooling jacket, a radiator and outgoing and return connections between said jacket and said radiator, a thermostatically controlled valve normally substantially closing said outgoing connections to flow, a conduit extending between said connections, and a pressure relief valve disposed therein, said valve being normally closed but being responsive to increases in pressure in said outlet connection.

2. In combination with an internal combustion engine, a cooling system therefor, comprising a fluid cooling jacket, a radiator and outgoing and return connections between said jacket and said radiator, a conduit extending between said connections, a thermostatically controlled valve disposed in said outgoing connection adjacent said conduit, said valve being normally closed, and a pressure relief valve disposed in said conduit, said latter valve being normally closed but

being responsive to increases in pressure in said outgoing connection.

3. In combination with an internal combustion engine, a cooling system therefor, comprising a fluid cooling jacket, a radiator and outgoing and return connections between said jacket and said radiator, a conduit extending between said connections and constituting with said jacket and connections an interior circuit from which said radiator is excluded, means normally closing both said entire system and said interior circuit to circulation of a cooling fluid, said means being responsive to pressure increases to open said interior circuit and to temperature increases to open said entire system.

4. In combination with an internal combustion engine, a cooling system therefor, comprising a fluid cooling jacket, a radiator and outgoing and return connections between said jacket and said radiator, and circulating means in circuit therewith, a thermostatically controlled valve means normally closing said system to circulation through said radiator, and pressure relief means adapted to relieve the system of the pressure built up by said circulating means during the closure of the system by said valve, said pressure relief means including connections to said outgoing and return connections.

5. In combination with an internal combustion engine, a cooling system therefor, comprising a fluid cooling jacket, a radiator and outgoing and return connections between said jacket and said radiator, and circulating means in circuit therewith, a thermostatically controlled valve means normally closing said system to circulation through said radiator, and means for establishing a circulation through said jacket upon a predetermined increase in pressure therein during the closure of said thermostatically controlled valve, said last means being actuated solely by the pressure in said jacket.

45 Signed by me, this 19th day of March, 1926.
HORACE B. FAY.
